US00D763358S

(12) **United States Design Patent**
Quick et al.

(10) **Patent No.:** US D763,358 S
(45) **Date of Patent:** ** Aug. 9, 2016

(54) **GAME BOARD**

(71) Applicants: **Scott G. Quick**, Rochester, NY (US);
James B. Rafferty, Rochester, NY (US)

(72) Inventors: **Scott G. Quick**, Rochester, NY (US);
James B. Rafferty, Rochester, NY (US)

(73) Assignee: **Bru-Bag, LLC**, Rochester, NY (US)

(**) Term: **15 Years**

(21) Appl. No.: **29/541,864**

(22) Filed: **Oct. 8, 2015**

Related U.S. Application Data

(63) Continuation-in-part of application No. 14/055,519,
filed on Oct. 16, 2013, now abandoned.

(57) **CLAIM**

We claim the ornamental design for a game board, as shown
and described.

DESCRIPTION

FIG. 1 is a top rear perspective view of one embodiment
according to the present game board;

FIG. 2 is a bottom front perspective view thereof;

FIG. 3 is a top view thereof;

FIG. 4 is a bottom view thereof;

FIG. 5 is a right side view thereof;

FIG. 6 is a left side view thereof;

FIG. 7 is a front view thereof; and,

FIG. 8 is a rear view thereof.

The large unshaded surfaces shown in FIG. 2 and the broken
lines shown throughout the views represent the portions of the
design that form no part of the claim.

1 Claim, 5 Drawing Sheets
